COIL WINDING APPARATUS

Polemon V. Riddle, Auburn, Ala.

Application May 3, 1938, Serial No. 205,856

3 Claims. (Cl. 140—92.2)

This invention relates to new and useful improvements in apparatus for winding and completely forming electric coils such as are used in semi-closed slot, three or two phase electric 5 motors of various sizes and speed.

The principal object of the present invention is to provide an apparatus upon which first, a coil can be wound, and secondly, formed to the desired shape in which the same will be used 10 in the electric machine.

Other important objects and advantages of the invention will become apparent to the reader of the following specification.

In the drawings—

Figure 1 represents a side elevational view of the machine.

Figure 2 is a top plan view.

Figure 3 is a fragmentary side elevational view with the machine about to be shifted to shape 20 the coil.

Figure 4 is a sectional view taken substantially on a line 4—4 of Figure 1.

Figure 5 is a fragmentary detailed sectional view taken substantially on a line 5—5 of Figure 25 2.

Figure 6 is a perspective view of the grooved bar.

Figure 7 is a fragmentary detailed sectional view through one of the joints.

Figure 8 is a sectional view on a line 8—8 of Figure 2.

Figure 9 is a fragmentary detailed sectional view on a line 9—9 of Figure 2.

Figure 10 is a fragmentary sectional view 35 through one of the sleeves.

Figure 11 is a cross section on the line 11—11 of Figure 2.

Figure 12 is a fragmentary side elevational view of the coil fastening means.

Figure 13 is a section taken substantially on a line 13—13 of Figure 2, without the lock rod.

Figure 14 is a section on the line 14—14 of Figure 12.

Figure 15 is a perspective view of the finished 45 coil.

Figure 16 is an end elevational view of the finished coil.

Figure 17 is a top plan view of the finished coil.

Referring to the drawings, wherein like numerals designate like parts, it can be seen in Figure 1 that the apparatus consists of end supports, each end support consisting of a pair of upwardly tapering frame structures 5—5, 55 these frame structures each formed with brace

means and having their front portions anchored as at 6 to a base 7. Suitable bridge members 8 are provided between the frame structures to support bearings 9 through which the vertical shaft 10 is disposed. There is a vertical shaft 5 at each end of the apparatus and the horizontal drive shaft 11 extends between the end supporting structures and through bearings 12 in the end supporting structures. The ends of the shaft 11 are equipped with bevel gears 13 which 10 mesh with bevel gears 14 at the lower end of the shafts 10. The upper ends of the shafts 10 are provided with bevel gears 15 which mesh with bevel gears 16 on the shafts 17 and 18 which are journaled through bearings 19 at the upper portions of the said end supporting structure. 15

A belt 20 is trained over the pulley block 21 on the armature shaft of the motor 22 and also over the pulley block 23 on the drive shaft 11, and obviously suitable clutch means desired may 20 be used in conjunction with this belt or in the drive shaft 11.

The shaft 17 is provided with the head portion 24 securing the block 25 through which the elongated shaft 26 is disposed, the intermediate portion of the shaft being secured to the block 25 by the set screw 27. As is clearly shown in Figure 6, the bar 26 is grooved inwardly from each end thereof as at 28 to a point adjacent the intermediate portion thereof. 30

At each side of the block 25 the bar 26 extends through a block 30 and each of these blocks 30 has a bore 31 therein at right angles to the bore receiving the bar 26. Each of these blocks 30 also has a set screw 32 for disposition into 35 the corresponding groove 28. A bar 33 extends through the bore 31 of each of the blocks 30 and each of these bars has smoothed side portions extending toward the ends of the bar from the intermediate undisturbed portion 34, 40 and these flattened portions are disposed through bores 35 in blocks 36. Set screws 37 engaged in the blocks 36 bear against the flat sides of the bars 33. 45

Laterally disposed lugs 38 serve to receive the 45 ends of the elongated coil engaging rods 39, each of these rods 39 carrying a plurality of collars 40 serving as coil spacing means.

The shaft 26 outwardly of the blocks 30 carries the blocks 41, one at each end portion of the bar 26. Each of these blocks 41 carries a set screw 42 for disposition in the corresponding groove 28 of the bar 26 and each of these blocks 41 is bifurcated as at 43 to receive the corresponding end of the rod 44. Each of these rods 50 55

44 carries a sleeve 45 from which a plurality of pins 46 extend in substantially the same spaced relation as the collars 40 on the rods 39. As shown in Figure 10, the rod 44 is provided with a tongue 47 for disposition into a longitudinally extending groove 48 in the sleeve 45. A set screw 49 on the sleeve can be driven against the rod 44 to prevent longitudinal adjustment thereof.

10 The remaining ends of the rods 44 are also equipped with the blocks 41 adjustably disposed on the grooved short bars 50.

Each of these blocks 41 carries a pair of pins 51—51a which extend through a slot 53 in the corresponding end of the rod 44 to secure the rods 39 against pivotal and endwise sliding movement and obviously to permit the apparatus to swing in forming a coil, one of these pins must be removed at each of the blocks 41 whereby 20 the wire carrying rods 39 may pivot and slide endwise.

As shown in Figure 8, the short shafts 50 each has its end portions provided with circumferentially extending grooves for receiving the set screw 50a in the arm 52 and also the set screw 53' in the block 54, the block 54 being formed with a bore 55 at right angles to the opening receiving the bar 50 for supporting the blocks 56 which carry the lugs 57 for receiving the remaining ends of the rods 39. Set screws 58 on the blocks 54 engage the rod 59 to prevent self-adjusting thereof.

The longitudinally grooved bar 60 is carried by the head structure 61 on aforementioned shaft 18 and this bar 60 is disposed through the end portions of the arms 52 and these arms are held in place by set screws 62.

It can be seen that the lugs 57 are swivelly connected as at 65 to the corresponding blocks 56 through which the bar 59 extends, the rod 39 being provided with a reduced portion 66 secured in the lugs 57 by set screws 67.

Obviously, in the operation of the apparatus, the wire is started onto the apparatus and the apparatus is rotated until all of the spaces between the lugs and pins have been filled with coils. Subsequently the set screws and certain of the pins 51—51a can be removed to permit the apparatus to be tilted down in the manner shown in Figure 3, in which action the coils 68 are brought to the desired form as shown in Figures 15, 16 and 17.

To hold the coils against slipping over the pins and collars, it can be seen that the collars are formed with extensions 69 recessed as at 70 for receiving the lock rod 71 which can be held in place by a clip-type spring 72. These clips and rods can be removed when the coils are to be removed.

60 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A winding apparatus comprising a supporting structure, end supporting bars carried by said supporting structure for rotation about a horizontal axis and releasably secured on said supporting structure whereby said bars may be rotated about an axis parallel thereto, rods mounted on said bars and extending at right angles thereto, wire supporting rods pivoted on said bars and movable endwise in opposite directions to each other by the rotation of said bars about axes parallel therewith and rotatable with the bars about the horizontal axis and including spaced wire engaging collars, wire supporting rods pivotally connected to said rods and including sleeves slidable thereon and provided with spaced wire-engaging pins, and means for releasably securing the second-named wire supporting rods against pivotal movement to secure the first-named wire supporting rods against endwise movement.

2. A winding apparatus comprising a supporting structure, opposed heads mounted on said supporting structure for rotation about a horizontal axis, bars rotatably mounted in said heads, means for securing said bars against rotation in the heads, rods mounted on said bars for endwise adjustment of said bars and extending at right angles to said bars, wire supporting rods paralleling each other and pivotally connected to said bars and adjustable endwise of each other in opposite directions by the rotation of the bars in the heads, wire supporting rods paralleling the first-named wire supporting rods and pivotally and slidably connected to said rods, and means for releasably securing the second-named wire supporting rods against pivotal movement for securing the first-named wire supporting rods against endwise movement.

3. A winding apparatus comprising a supporting structure, opposed heads mounted on said supporting structure for rotation about a horizontal axis, bars rotatably mounted in said heads, means for securing said bars against rotation in the heads, rods mounted on said bars for endwise adjustment of said bars and extending at right angles to said bars, wire supporting rods paralleling each other and pivotally connected to said rods and adjustable endwise of each other in opposite directions by the rotation of the bars in the heads, blocks mounted on said bars and having bifurcated portions, wire supporting rods paralleling the first-named wire supporting rods and having slotted ends received in the bifurcations of the blocks, and pins extending through the bifurcations of the blocks and the slotted ends of the second-named wire supporting rods to secure the first-named wire supporting rods against endwise movement and certain of said pins being removable to permit the first-named wire supporting rods to have endwise movement.

POLEMON V. RIDDLE.
